5 Claims. (Cl. 61—45)

This invention relates to linings for earth borings and, in particular, to a liner segment adapted to be formed from steel plate and to be assembled end to end with other similar segments forming 5 continuous lining rings. Such rings are assembled side by side in a manner to form a complete lining.

Numerous forms of liner segments have been proposed heretofore and it is the principal object 10 of our invention to improve upon the segments which have been used previously both from the standpoint of economy of manufacture and ease and convenience in erection, while at the same time providing a segment of ample strength to 15 support the load to which linings are usually subjected.

Linings for earth borings are subject to certain well defined forces, such as ring thrust, ring bending, bending of segments, etc. Ring thrust 20 is the circular thrust going around the ring setting up compression stresses in the metal. This ring thrust is distributed over the sectional area of the segment and must be transmitted across the joints between the segments of each ring. 25 Bending is caused by unequal loading of the ring and is resisted by the section modulus of the segment. The joints between segments of each ring must be strong enough to withstand the bending force. Staggering of the joints in 30 the adjacent courses is of assistance in this respect, each course acting as a splice for the adjacent course. Local bending of individual segments is resisted by the section modulus of the segments taken circumferentially of the lining. 35 It will be seen, therefore, that the strength of the joints is of extreme importance.

In a preferred form of the invention, our liner segment comprises a curved plate having stiffening corrugations extending therealong, preferably though not necessarily throughout the entire length thereof. End walls extend inwardly from the plate adjacent the ends thereof, in one form of the invention, one of said walls being located substantially at one end of the plate, the other being spaced inwardly from the other end thereof. Securing means such as bolts passing through the end walls connect adjacent plates rigidly together. Each segment is overlapped by one of the other adjacent segments. 50 These structural features provide the strength necessary to resist the forces above mentioned. In another form of the invention we dispense with the end walls and provide means for rigidly connecting the segments end to end, as will be described in greater detail hereafter, with refer-

ence to the accompanying drawings illustrating a preferred embodiment as well as the modification thereof. In the drawings:

Fig. 1 is a partial side elevation of a lining composed of segments of the preferred form; 5

Fig. 2 is a partial plan view thereof;

Fig. 3 is a sectional view taken along the line III—III of Fig. 2;

Fig. 4 is a sectional view taken along the line IV—IV of Fig. 2; 10

Figs. 5 and 6 show adjacent segments in section as in Fig. 4 but separated from each other instead of connected together;

Fig. 7 is a partial side elevation of one end of the segment to an enlarged scale; 15

Fig. 8 is a partial plan view of a lining composed of segments of a modified form;

Fig. 9 is a partial sectional view taken along the line IX—IX of Fig. 8;

Fig. 10 is a similar view taken along the line X—X of Fig. 8; 20

Fig. 11 is a radial sectional view taken through a segment along the line of the bolt holes adjacent one end;

Fig. 12 is a similar view taken along the line 25 of the bolt holes adjacent the other end; and

Fig. 13 is a view similar to Fig. 3 showing a further modification.

Referring now in detail to the drawings, and, for the present to Figs. 1 through 7, a lining for 30 a tunnel or the like in accordance with the invention is indicated generally at 10. The lining is composed of segments 11 assembled end to end to form rings such as indicated at 12 and 13. These rings are built up in side by side relation to the desired length within the tunnel 35 or other boring.

The segments 11 are formed from steel plate and are provided with corrugations 14 which preferably extend the full length of the plates. 40 As shown in Fig. 1, each segment includes a skin plate curved to the desired radius, and end walls 15 and 16 extending inwardly therefrom. Both end walls are shaped to conform to the corrugations of the plate as shown in Fig. 3 45 and are welded to the plate as at 17. As shown in Fig. 6, the end wall 15 is welded to the skin plate flush with the end thereof. The end wall 16, however, as shown in Fig. 5, is welded to the skin plate in a position spaced inwardly from 50 the other extreme end thereof. By virtue of this position of the end wall 16, one end of each segment (the right hand end shown in the drawings) overhangs the end of the adjacent segment as at 18 in Fig. 4. The end walls are provided 55

with aligned holes adapted to receive connecting bolts 19 by which the abutting ends of two adjacent segments may be drawn firmly together and rigidly connected. The rigidity of this connection provides sufficient strength in the completed lining to withstand the stresses to which it is normally subject and makes each ring of the lining self-supporting as it is erected, the connection between segments being such that stress applied to one segment is communicated across the joints between it and adjacent segments to the remainder of the ring. The end-to-end joint shown is 100% efficient in transmitting thrust around the ring. Bolts 19a traversing the lapped ends of the segments make the joint highly efficient also in resistance to forces tending to cause bending of the rings. The overlapping portion 18 of each segment provides a tight joint between the ends of adjacent segments to prevent infiltration therebetween.

Intermediate transverse reinforcing members 15a may be welded to the segments to provide additional resistance to bending.

In addition to the end walls 15 and 16, the segment has side walls 20 which may conveniently be formed by bending down the edges of the plate forming the body of the segment. Because of the shape of the corrugations 14, the lapped portions of adjacent plates will nest closely as shown in Fig. 3. Since the side walls of plates assembled in end to end relation are in the same plane, however, portions of both side walls of each segment are cut out adjacent the end wall 15 as indicated at 21 to receive the overhanging side walls of the adjacent segment as shown in Fig. 4. The side walls are also provided with bolt holes whereby each ring may be connected to the adjoining rings by bolts 22.

It will be apparent from the foregoing description that the segment shown in Figs. 1 through 7 makes it possible, at relatively low cost, to provide a strong, rigid lining for earth bores characterized by tight joints and relatively light weight. The facility with which the lining may be erected is a further important advantage because the work of assembly is performed within the lining where working space is very limited.

Referring now to Figs. 8 through 12, a modified form of segment 30 is provided with side walls 31 and corrugations 32 extending throughout the length thereof. The segment 30 is curved longitudinally in the same manner as the segment 11 and has intermediate transverse reinforcing members 30a similar to those shown at 15a. Opposite ends of each segment are provided with depressions or protuberances 33 and 34 so shaped and dimensioned that they form mating portions, as shown in Figs. 9 and 10, when the ends of adjacent segments are lapped for connection as by bolts 35 extending through aligned holes in the depressions 33 and 34. The depressions are preferably formed in the crests and troughs of the corrugations which are substantially flat. For convenience in assembling the segments, nuts 36 are welded in the depressions 33 at one end of each segment. The bolts 35 may thus be inserted from inside the lining and screwed home tight without any difficulty. Bolts 37 extending through aligned holes in side walls 31 serve to connect adjacent rings of the lining in the manner already explained.

The segment shown in Figs. 8 through 12 is characterized by all the advantages aforementioned with reference to the form of the invention first described, as well as the additional advan-

tage of still lower cost in that no end walls are employed. The mating recesses 33 and 34 make the end-to-end joints efficient in transmitting thrust and the bolts passing through the crests and troughs of the corrugations are likewise very efficient in transmitting bending stress.

A further form of the invention is illustrated in Fig. 13. This form is similar to that of Figs. 8 through 12 in all respects except that it has no side wall as such, the edges of the segments of adjacent rings being lapped as at 40, one edge of each segment being pressed downwardly as at 41 to permit such lapping. The lapped edges are connected by bolts 42 and the nuts 43 cooperating therewith may be welded to the edges of the segments in alignment with the bolt holes to facilitate assembly.

While we have illustrated and described herein only a preferred form of the invention with two modifications thereof, it will be understood that various other changes in the invention disclosed may be made without departing from the spirit thereof or the scope of the appended claims.

We claim:

1. A liner segment comprising a skin plate 25 curved along one dimension and having corrugations extending along said dimension, depressions formed adjacent one end of the plate and protuberances at the other, a pair of said segments being adapted to be assembled end to end in partly lapped relation wherein the protuberances at one end of a segment mate with the depressions in the end of the adjacent segment, said depressions and protuberances being disposed at the crests and troughs of said corrugations.

2. A lap joint connecting the edge of one plate to the edge of an adjacent plate, said plates being curved along their dimension perpendicular to their lapping edges and having corrugations extending in the direction of curvature, said joint including depressions spaced apart along the lapping edge of said one plate, protuberances similarly spaced along the lapped edge of the adjacent plate, said protuberances nesting in said depressions when the edge of said first-mentioned plate is in lapping relation to the edge of said adjacent plate with their corrugations nesting, and means securing the lapped edges of said plates together, said depressions and protuberances being tapered whereby they nest tightly.

3. A liner segment comprising a curved metal plate having corrugations extending along one dimension thereof, said corrugations being deformed adjacent their ends to provide protuberances and sockets adapted to interfit on lapping the end of one segment over the end of another.

4. A liner segment comprising a curved metal plate having corrugations extending along one dimension thereof, said corrugations having troughs and crests defined by cylindrical surfaces and connecting portions extending therebetween defined by conical surfaces.

5. A liner segment comprising a curved metal plate having corrugations extending along one dimension thereof, said corrugations being deformed adjacent their ends to provide protuberances and sockets adapted to interfit on lapping the end of one segment over the end of another, and holes through said plates adjacent said protuberances and sockets, adapted to receive fasteners for securing adjacent plates together in end lapped relation.
